COASTER FOR MILK CARTONS OR THE LIKE

Joseph Bernabo, Pittsburgh, Pa.

Application February 21, 1957, Serial No. 44,946

Term of patent 7 years

(Cl. D44—10)

Fig. 1.

Fig. 2.

Fig. 1 is a perspective view of a coaster for milk cartons or the like showing my new design;

Fig. 2 is an edge elevational view thereof, a milk carton being shown in broken lines for illustrative purposes only.

A characterizing feature of the design resides in the outwardly flaring corner portions in their relation to and association with arcuate cuts in the sidewalls, all as shown.

I claim:

The ornamental design for a coaster for milk cartons or the like, substantially as shown and described.
